PUMPING SYSTEM

Application filed July 14, 1930. Serial No. 467,830.

The present invention relates generally to pumping systems, and more particularly to pumping systems capable of handling a mixture of liquid and gas. Specifically, the present invention contemplates the provision of an improved pumping mechanism for maintaining a vacuum upon the radiators of a steam heating system and for returning the water to the boiler.

As is well known to those skilled in the art, steam heating systems are now commonly in use employing steam at a relatively low boiler pressure and employing a vacuum circulating pump for maintaining a circulation to the radiators and for withdrawing the condensate and waste steam, if any, together with any air which may leak into the system. In such installations it is desirable to return the condensate to the boiler, but it is undesirable to direct any of the air into the boiler. It is therefore essential to separate out the air, condense the steam which is not already condensed and return the total condensate to the boiler.

In my previous patent, No. 1,674,115, issued June 19, 1928, I disclosed an improved steam heating system including a novel pumping apparatus for maintaining a vacuum upon the return line, separating out the air, condensing the steam and returning the condensate to the boiler. The system there disclosed employed a relatively small high speed centrifugal pump capable of pumping gas, vapor, or liquid, or a mixture of them, and produced a positive suction when pumping any of said fluids. One object of the present invention is to provide an improved construction of that type and one which is simple and inexpensive yet exceedingly effective in operation.

Other objects and advantages of my invention will be apparent to those skilled in the art after a consideration of the following detailed description of the same, taken in conjunction with the accompanying drawings, in which:

Figure 1 is a diagrammatic view illustrating one embodiment of my invention; and

Figure 2 is a diagrammatic view illustrating another embodiment of my invention.

Referring now to the drawings, the reference numeral 1 indicates in its entirety a centrifugal pump having an intake 2 and an outlet 3. Preferably, the pump 1 is of the type shown in my prior Patent No. 1,578,236, issued March 28, 1926, but this is not entirely necessary in the pumping system of the present invention. Any self priming pump or any pump which will handle some air will be satisfactory and, as a matter of fact, my improved system can be made to operate with a pump which will not handle air, although pumps of the first type are preferable.

The outlet or return line from the radiators is indicated by the reference numeral 5, and this actually forms the inlet side of the pumping system as a whole. Check valves 6 provide a one-way flow from the line 5 through the intake branches 7 of the pumping system. A pair of chambers or containers 9 are shown as connected at their upper ends to the intake conduits 7, as by means of short sections 10. The sections 10 are so connected that they are also in communication with the outlet conduits 12 of the pumping system, these outlet conduits being connected to the boiler by means of a discharge line 13.

As illustrated in the drawings, these conduits 7 and 12 are shown as connected to a radiator return 5 and a single boiler line 13, respectively, but it is obvious that the conduits 7 and 12 may have separate leads connected thereto if found desirable or necessary.

The containers 9 are each provided with a valve 15 having a ball 16 at the upper end and a float 17 at the lower end, the ball 16 and float 17 being connected to one another by means of a stem 18. The ball 16 is provided with a closure 20 adapted to be received by a correspondingly formed apertured seat 21 provided at the upper part of each of these containers or chambers 9. The particular function of this valve, as will be better understood later, is to allow the escape of gas from the container or chamber 9 but to prevent the escape of liquid therefrom, this being accomplished by virtue of the buoyancy of the float 17 which, rising with the level

85

90

95

100

of the liquid in the chamber 9, serves to close the opening at the top of said chamber.

The lower part of each of the containers or chambers 9 is adapted to be placed in communication with the intake and the outlet of the pump 1 alternately by a system of conduits and interlocked valves which will now be described. Leading from the bottom of each chamber 9 is a conduit 20 and each of these conduits 20 is connected to a branch 21, which in turn, leads to a two-way valve 22. Similar branches 24 place the conduits 20 in connection with a second two-way valve 26, as will be clear by referring to the drawings.

The valve 22 is connected with the outlet 3 of the pump by means of a branch 29 and the valve 26 is connected with the intake 2 of the pump by means of a branch 30.

The valves 22 and 26 are connected together by means indicated diagrammatically by the reference numeral 32. It is desirable that these valves operate simultaneously, and in order to secure this result each valve may be provided with a pulley or sprocket wheel over which is trained a chain or belt. My invention also contemplates mounting these valves 22 and 26 on the same shaft and, actually, this construction is the preferable form. As above stated, the valves 22 and 26 are of the two-way type, sometimes known as the two port type, and these valves are shiftable from one position to another so that flow from branches 29 and 30 can be directed, respectively, to branches 21 and 24 in either one direction or the other.

The operation of the structure so far described is as follows. As illustrated in Figure 1, it being assumed that the pump 1 is in operation, liquid is withdrawn from the right hand chambers 9 through the branch 20 at the branch 30 and passing through the pump 1 is then directed upwardly through branch 29 past the valve 22 which directs the liquid to the left, as viewed in Figure 1, to the branch 21 and into the left hand chamber 9. Since the buoyancy of the float 17 serves to hold the valve 20-21 closed, the liquid is forced to pass out of a chamber 9 through the section 10 and past the check valve 11 which permits only outward flow into the outlet conduit 12 and the boiler line 13, from which the liquid is passed back into the boiler.

When the valves 22 and 26 are shifted to their other position, and this is the position illustrated in Figure 2, the operation of the pump 1 withdraws liquid from the left hand chamber 9 down through the conduit 20, through the branch 24, past the valve 26, into the conduit 30 and into the intake side 2 of the pump 1. In the meantime the liquid discharged through the outlet 3 of the pump 1 passes through the conduit 29, past the valve 22, to the right in the branch 21 and upward-

ly through the conduit 20 and into the chamber 9 on the right hand side, as viewed in Figure 2.

Digressing for the moment, I shall now describe the control means for automatically shifting the interlocked valves 22 and 26. Turning to Figure 1 it will be observed that a pipe 35 opens into communication with the conduit 29 near the discharge side 3 of the pump 1. The outer end of the pipe 35 is connected to a diaphragm chamber 36 containing a diaphragm 37, the latter being flexible yet substantially liquid and gas tight. The pipe 35 leads into the lower part of the diaphragm chamber 36 and below the diaphragm 37 therein, while the upper part of the diaphragm chamber 36 is provided with a port 39 through which rises a stem 40 connected at its lower end to the diaphragm 37. A spring 42 is connected at one end to the stem 40 to urge the same downwardly, the spring 42 being tensioned between the stem 40 and an abutment 44 fixedly mounted upon any stationary part, such as a casing 45 enclosing the valve shifting mechanism proper.

Mounted in the casing 45 is a ratchet wheel 47 provided with a plurality of ratchet teeth 48 which are adapted to be consecutively engaged by a latch or pawl 49 pivoted to the stem 40 near the upper end thereof. The ratchet wheel 47 may have an outer periphery in the form of a pulley over which is trained a belt 51 having a connection with the interlocked valves 22 and 26 in any manner desired.

It is to be understood, however, that the motion transmitting mechanism operatively extending between the stem 40 and the valves 22 and 26 may take any form desired and that the particular structure just described is only one conventional way of securing the result of controlling the valves 22 and 26. Obviously other means may be provided for the same purpose, for instance, the shaft upon which the valves 22 and 26 are fixedly secured may be extended and directly connected to some form of ratchet mechanism, such as that indicated by the reference numerals 47 and 48. It is desirable that in practice the valves be shifted with a snap action and for that purpose a spring, spring cage, catch and trip of the type shown in Pfau Patent No. 1,090,873 or Perry Patent No. 933,200 may advantageously be employed. Also, as illustrated in those patents, the rotary valve or valves may be replaced by a plurality of poppet valves.

Furthermore, while I have shown the pipe 35 opening into the outlet pipe 29, it is contemplated that the pipe 35 may be connected directly to the pump, preferably the discharge throat thereof, or any other point subject to the discharge head or the impact pressure of the discharge.

Another form of valve shifting mechanism

is illustrated in Figure 2, this form being electrically operated. Mounted in each of the chambers 9 is a float 60, preferably pivot-ed for vertical swinging to a portion of the 5 chamber or container itself. The float is provided with a contact arm 61 having there-on a pair of contacts 62 adapted to complete an electric circuit to fixed contacts 64, as is well understood in the art. The contacts 64 10 are a part of an electrical system including conductors 66, the armature and field of a reversing motor 67 and leads 68 connected with a power line. As clearly shown in Figure 2, the float 60 in the left hand chamber 9 is provided with a similar system of contacts 62 which, like the contacts 62 of the right hand chamber 9, are adapted to close an electric circuit through conductors including fixed contacts 64. The conductors 66 for the 15 left hand chamber 9 lead to the armature of the reversing motor and to a separate field of the same, as indicated in Figure 2. As is well understood in the art, the motor 67 may be driven in one direction or the other, de-pending upon which one of the fields is acti-vated by directing a flow of current there-20 through. The motor 67 is connected by any suitable means 70 to the interlocked valves 22 and 26. This motor or the valves 22 and 26 25 may be provided with suitable contacts actuated by predetermined motion of its shaft sufficient to shift the valves 22 and 26 to transfer the control of its actuating cir-cuit from one float switch to the other float 30 switch, so that shifting of the valves 22 and 26 is under the alternate control of the two float switches. Also, instead of reversing the direction of drive, the motor may drive in the same direction in successive steps.

As stated above in connection with the embodiment illusbraed in Figure 1, any suitable means may be employed to transmit motion between the reversing motor 67 and the interlocked valves 22 and 26, and it is to be understood that while I have shown one conventional structure for shifting the valves 22, 26 any equivalent structure falls within the scope of my invention.

The operation of my complete pumping system is as follows. When the valves are in the position illustrated in Figure 1 the operation of the pump 1 draws condensate from the radiators through the return outlet 5 into the right hand conduit 7 forming the intake of my improved pumping system. The suc-tion applied is effective to lift the check valve 6 allowing the condensate, together with any air drawn into the heating system, to flow 55 through the short section 10 and into the right hand chamber 9. The suction created by the pump withdraws liquid from the right hand chamber 9, which liquid actually acts as a liquid piston in the container 9. The 60 air and liquid condensate separate in the

chamber 9, the chamber 9 thus acting as a trap to retain the air and other gases in the top of the chamber while the separated liquid falls to the bottom of the chamber and is withdrawn therefrom by the action of the 70 centrifugal pump 1. In normal operation, however, the amount of liquid drawn into the pumping system is not sufficient to supply the demand of the pump 1. This occasions a fall of the liquid level in that chamber and, 75 as is well understood in the art, as soon as air passes over from the chamber 9 into the conduits 20 and 30 and from thence into the pump 1 the discharge pressure thereof imme-diately falls. As soon as this occurs the 80 pressure on the lower side of the diaphragm 37 previously maintained by virtue of the discharge pressure of the pump is suddenly released and the spring 42 immediately moves the stem 40 downwardly. The down-ward movement of the stem 40 causes the latch or pawl 49 to engage one of the teeth 48, thereby causing the wheel 47 to make a given forward angular movement which, in turn, drives the valves shifting means 32 to 85 swing the valves 22, 26 to their opposite position, this position being the same as that shown in Figure 2. By virtue of the sudden release of the discharge pressure due to the introduction of gas in the intake, the shift-ing of the valves 22, 26 is, as a practical proposition, substantially instantaneous. As soon as the valves 22 and 26 are shifted from the position shown in Figure 1 to a position 90 corresponding to that shown in Figure 2 the intake 2 of the pump 1 is connected through the conduit 30, the left hand branch 24, and the conduit 20 to the left hand chamber 9 which, as shown, is filled with liquid. As soon as the suction of the pump is exerted upon 95 the left hand chamber 9 the check valve 11 closes. This prevents any back flow of liq-uid from the boiler line 13. The continued suction of the pump 1 withdraws liquid from the chamber 9, and since no more liquid can 100 enter from the boiler line 13 suction is cre-ated within the left hand intake conduit 7, thus lifting the check valve 6 and at the same time closing the check valve 6 on the other side. Where before suction was applied to 105 the radiator return line 5 through the right hand chamber 9 and the right hand conduit 7, suction is now applied to the same return line 5 through the left hand container 9 and the left hand conduit 7. As the level of liq-110 uid in the container 9 continues to fall the valve 15 is allowed to fall, but air is prevent-ed from entering the container 9 by virtue of the gas tight seat effected between the wall 115 16 and the valve seat 19. In the meantime the pump 1 has been discharging liquid out the outlet 3 into the conduit 29 and passing the same to the right to the branch 21 and back into the right hand chamber 9. The 120 level of liquid in this chamber therefore rises 125 130

and, acting as a liquid piston, first drives the air and gas therein out through the port 21 and lifts the ball 16 from its seat 19. As the pump 1 continues to operate the level in the right hand container 9 rises more and more, driving more air and gas from the container, because less resistance is met in lifting the valve 16 and driving the air and gas to atmosphere than is met in forcing the air through the upwardly opening check valve 11 and against the head of liquid and the boiler pressure in the boiler line 13.

When the level of liquid in the right hand container 9 approaches the top thereof, substantially all the excess air and gas has been expelled, and as the float 17 rises the port 21 is closed, so that liquid can not escape to the atmosphere but is forced to pass through the short section 10 and, the right hand valve 6 being already closed, is directed through the right hand check valve 11 and up the outlet conduit 12 into the boiler line 13. The other check valve 11 effectively resists any tendency for the liquid to pass down the left hand conduit 12 and into the left hand chamber 9, thus assuring that the liquid will be directed to the boiler.

It is thus obvious that the falling liquid level in the left hand chamber 9 will act as a liquid piston drawing in condensate and air from the radiator return line while the rising liquid level in the right hand chamber 9 acts as a liquid piston to, first, expel excess air and gases from the chamber and, second, to direct a quantity of liquid to the boiler line 13. When the liquid level in the left hand chamber 9 falls to such an extent that air is drawn into the intake 2 of the pump the pressure on the outlet side thereof immediately falls, which reduction instantaneously allows the spring 42 to force the stem downwardly, thereby shifting the interlocked valves to the opposite position.

In effect, therefore, I provide a pumping system employing a pair of liquid pistons which are alternately raised and lowered by an actuating mechanism including a pump. An important feature of the present invention is that the liquid drawn in by the operation of the pumping device is added to the residual liquid in the chambers and that the pump operates to force the liquid in one direction until the supply thereof from the other direction is substantially depleted. Thus while the pumping system itself operates with a predetermined quantity of liquid, the amount of liquid added thereto by the intake system from the return lines will cause an equal amount of liquid on the other side of the system to be forced back into the boiler. In addition, on the upstroke of the liquid system excess gases and uncondensed vapors are removed from the chambers containing the liquid pistons so that there is no likelihood of forcing anything but liquid into the boiler.

This is an important feature of the present invention. The structure provided thus acts not only as an efficient pumping system but also as a means for separating a gas and a liquid when they are received as a mixture. With this in mind it will be observed that the present invention may be employed in installations entirely different from steam heating systems. For example, the present disclosed apparatus can be employed where the principal function thereof is to separate a gas from a liquid. For example, where the present system has been described as connected to a steam boiler on the discharge side of the system and to the radiator return line on the intake side of the system, it is possible to connect the intake side of the system directly to the discharge side interposing for that purpose, a simple container which would supply only a sufficient head to be adequate to cause the rising liquid piston to force the excess gas out the valve 15 rather than through one of the check valves 11 and into the container. In this way the present apparatus would function efficiently as a gas and liquid separator. Furthermore, if the gases to be expelled contain valuable substances it would be a simple matter to connect leads to the ports 21 so as to direct these gases to some point of utilization.

It is to be understood, of course, that the electrically operated mechanism for shifting the interlocked valves is only one of many different means which might be utilized for the same purpose and which are intended to be embraced by the present invention. For example, the shaft or other connecting means by which valves 22 and 26 are interlocked might be operated by a simple solenoid and relay system, under the control of the pressure elements 37 or under the control of the float controlled switches 61—64, as is well understood in the art. Furthermore, such a system can be made to be responsive, primarily, to either a fall of pressure on the discharge side of the pump or to a predetermined low level of liquid in the chambers 9. It should be here pointed out, however, that whether the valve shifting mechanism is made responsive, initially, to a fall of pressure or fall of liquid level in the chambers 9, either of such valve operating mechanism is actually responsive to an excess of gas compared to the liquid in the chamber. This will be understood by comparing Figures 1 and 2. In Figure 1, when the level in either chamber 9 falls sufficiently to allow air to be drawn into the pump, the valve shifting mechanism operates to reverse the flow and draw the liquid out of the filled chamber and direct it into the emptying chamber; and in Figure 2, when the level falls sufficiently to cause the float arm 61 to complete the electric circuit, the valves

are shifted to reverse the flow in the manner just indicated. Thus, in either modification, it is the proportion of gas to liquid in the chamber which controls the shifting of the 5 actuating mechanism and the proportion of gas to liquid in the fluid coming from the radiators through return pipe 5 which controls the rate of making strokes by shifting of the valves.

10 It is to be noted that with either of the valve shifting mechanisms just mentioned, and which are shown in the drawings, the actual reversing of the valves is in practice made practically instantaneous. It has been 15 pointed out above that as soon as any air or gas obtains access to the pump 1 the discharge pressure immediately falls; hence the valves 22 and 26 are immediately shifted. In the modification illustrated in Figure 2, as soon 20 as the level in either chamber reaches a predetermined minimum, the circuit is closed and the valves are immediately shifted. It is to be understood, moreover, that any other form of snap action may be substituted such 25 as, for example, a spring placed under tension and released after a given stress or position has been reached, as is common in the art.

It is also to be understood that, instead of 30 separate branches 21 and 24, these branches might take the form of conduits cast or otherwise formed in a single manifold, in which case the valves 22 and 26 would preferably be formed as a structural whole.

35 There is contained in this system a peculiarly neat concept of means and mode of pumping a mixture of gas and liquid in that the liquid can mingle with and become a part of the displacing medium. At each 40 stroke the excess of liquid is removed and just the right amount of displacing medium retained, but the system is operative whether the two chambers are alike or not.

In the form shown in Figure 1 the pump 45 1 may actually exert a suction, as it is a self priming pump, but the system does not require a self priming pump, a straight centrifugal pump developing sufficient pressure to discharge the liquid into the boiler being sufficient.

Also, instead of making the system double acting, it may be made single acting. For example, in Figure 2, if the right hand tank 55 is made large enough to serve as a reservoir between discharge strokes it may serve merely as a liquid receiving tank.

The chambers 9 are the actual pumping chambers and it is in them that the suction 60 is produced which causes the inflow of gas and liquid. The gas and liquid then separate and are stratified by gravity, the liquid being added to the liquid piston which then is raised to expel the gas and finally to expel a 65 part of the liquid in excess of that required

to fill the chambers. I believe that this mode of operation is broadly new.

The motor of the pump 1 may be under the control of a vacuum gauge or suction responsive element so that where a predetermined vacuum has been attained the pump 1 may be stopped. This might cause shifting of the valves 22, 26 but the system may be started into operation in any position without difficulty by merely starting the 70 pump 1.

75 While I have described in connection with the accompanying drawings the preferred embodiments of my invention, it is to be understood that my invention is not to be limited to the structure shown or described, but that, in fact, widely different means may be employed in the practice of the broader aspects of my invention.

80 What I claim, therefore, and desire to secure by Letters Patent is:

85 1. The method of pumping a mixture of gas and liquid which comprises trapping said mixture in two separate bodies to separate the gas and liquid in each, pumping out 90 the liquid from one body until gas passes over, pumping liquid from the second body and directing the same into said first body whereby to drive off the gas, continuing said pumping until gas passes over from the second body, reversing the pumping operation to again pump liquid from the first body into the second to drive off the gas therein, and continuing said pumping operation until gas 95 passes over from the first body.

100 2. In a pumping system having an inlet line and an outlet line and a pair of valved traps therein, the method of operation which comprises alternately drawing a mixture of liquid and gas from said inlet line into said 105 traps in series, alternately employing one of said traps to separate the gas and liquid, directing the trapped gas to a point of discharge at each alternation by pumping liquid into the trap containing the gas from the other trap and from the inlet line and continuing the flow until substantial failure of the pump due to excess gas, and then reversing the pumping operation.

110 3. A system for pumping a mixture of gas 115 and liquid, comprising, in combination, a centrifugal pump, a pair of chambers, an intake conduit system, an outlet conduit system, valved connections connecting said chambers to said systems and said pump and including 120 a pair of interlocked valves operable to connect the inlet side of the pump to said intake conduit through either chamber and to connect the discharge side of the pump to the outlet conduit system through the other of 125 said chambers, and means including relief valves for the chambers and responsive to the discharge head of said pump for shifting said interlocked valves to reverse the connections between the chambers and said pump 130

and conduit systems whereby gas trapped in the chamber initially forming a continuation of the intake conduit is expelled as said chamber is connected to the discharge side of the pump when said valves are shifted.

4. In a system of the class described the combination of a pair of liquid containers, a pump, connections from the containers to a discharge line and to an intake line, valve means controlling said connections, and pressure responsive means connected to said pump and operative to control said valves to alternately withdraw liquid from one of said containers and direct it to the other.

5. In a system of the class described the combination with an intake line and a discharge line, of a pump, a pair of containers, each having valve means operative to allow the egress of gas and to prevent the egress of liquid, reversible connections between the inlet and outlet of said pump to said containers, whereby each of said containers are adapted to form a continuation of said intake or discharge line alternately, connections from each of said containers to the intake line and to the discharge line, and means responsive to discharge pressure of the pump for controlling said connections.

6. In a pumping system of the class described the combination with an intake line and a suction line of a pair of containers connected in and forming a part of said lines, a liquid tight gas outlet valve near the top of each container, a pump, connections between said containers and the pump and lines whereby a mixture of gas and liquid may be drawn in through either of said containers and liquid discharged through the other, and electrically operated means responsive when gas reaches a certain point in the suction line through which the mixture is being admitted for reversing said connections, thereby directing liquid into the last mentioned container and expelling the gas therein through the valve associated with that container.

7. In a system for pumping a mixture of gas and liquid, means forming a pair of liquid pistons, a pump for alternately raising and lowering said pistons, an inlet line and an outlet line, valved connections operatively connecting the pistons to said lines, and means responsive to the discharge head of said pump for controlling said valved connections.

8. A system for pumping a mixture of liquid and gas comprising, in combination, a pump, intake and delivery lines connected therewith, a plurality of valved containers each adapted to be connected to said lines, shiftable valve means alternately connecting the containers with the pump, loaded means biased to shift said valve means, and means controlled by the discharge head of said pump and adapted to prevent movement of said loaded means to shift the valve means as

long as liquid is discharged from said pump.

9. In a system for pumping a mixture of liquid and gas comprising, in combination, a pump, intake and delivery lines connected therewith, a plurality of valved containers each adapted to be connected to said lines, shiftable valve means alternately connecting the containers with the pump, a movable member the movements of which are adapted to shift said valves, and pressure responsive means connected to the discharge side of said pump for controlling said movable member.

10. A system for pumping a mixture of liquid and gas comprising, in combination, a pump, intake and delivery lines connected therewith, shiftable valve means alternately connecting the containers with the pump, and means adapted to shift said valve means when there is an excess of gas in the system.

11. In a pumping system including a liquid pump, a plurality of sources of liquid supply, and operable connections putting said pump into communication with either of said sources, the method of controlling said connections in accordance with the discharge head of the pump.

12. In a pumping system including a liquid pump including intake and discharge passages, a plurality of sources of liquid supply, and operable connections putting said pump into communication with either of said sources, the method of controlling said connections in accordance with the pressure in one of said passages.

13. In a pumping system including a liquid pump having intake and discharge passages, a plurality of liquid holding containers, operative connections between each of said containers whereby each of said containers may be placed in communication with said pump, and means responsive to the pressure in one of said passages for controlling said operative connections.

14. In a pumping system, means forming a pair of liquid pistons, a self priming pump capable of handling gas and liquids and including intake and discharge passages, valved connections operative to place said passages in communication with said means, and pressure responsive mechanism for controlling said valved connections, said mechanism being responsive to pressure in at least one of said passages.

15. A pumping system for pumping a mixture of gas and liquid comprising, in combination, a self priming pump, intake and delivery lines connected therewith, a plurality of valved containers each adapted to be connected to said lines, valve means alternately connecting the containers with the pump, and means responsive to an excess of gas in the system for controlling said valve means.

16. In an apparatus of the class described, a fluid pump, a pair of liquid receiving

chambers, valved connections between the pump and chambers, and means responsive to the complete exhaustion of liquid from one chamber by the pump for automatically shifting said connections.

17. In a system embodying a mixture of gas and liquid, the method of pumping which comprises trapping the mixture and at least partially separating the gas and liquid into two bodies, pumping out the liquid until gas passes over, and then reversing the pumping operation and expelling the separated gas.

18. In a system embodying a self-priming pump capable of handling a mixture of gas and liquid and a conduit for confining the same, there being a container disposed in and forming a part of said conduit, the method of pumping which comprises trapping the mixture in said container and at least partially separating the gas and liquid into two bodies therein, pumping out liquid from the liquid body until gas passes over, and reversing the pumping operation to expel the gas.

19. In a system embodying a self-priming pump capable of handling a mixture of gas and liquid and conduit means for confining the same, the method of pumping which comprises trapping the mixture and at least partially separating the gas and liquid into two separate bodies, pumping out the liquid from the liquid body until gas passes over, next reversing the pumping operation and expelling the separating gas until the liquid in the conduit means reaches a certain point, then again reversing the pumping operation.

20. In a pumping system of the class described the combination with an intake line and a suction line of a pair of containers connected to said lines, a liquid tight gas outlet near the top of each container, a self-priming pump, connections between said containers and the pump and lines whereby a mixture of gas and liquid may be drawn in through either of said containers and liquid discharged through the other, and means responsive to the ratio of gas to liquid in the container through which the mixture is being admitted for reversing said connections, thereby directing liquid into the last mentioned container and expelling the gas therefrom.

21. Means for pumping a mixture of gas and liquid comprising, in combination, inlet and outlet conduit means, a self-priming pump, a pair of chambers, means alternately placing each chamber between said pump and the inlet conduit means and between said pump and the outlet conduit means comprising shiftable connections, and hydraulic head responsive means for shifting said connections.

22. A system for pumping a mixture of liquid and gas comprising, in combination, intake and delivery conduit means, a pair of containers each adapted to be alternately con-

nected in said intake and delivery means, reversible connections to effect alternate connections, a liquid pump disposed below said containers, and means responsive to the exhaustion of liquid from the containers for reversing said connections.

In witness whereof, I hereunto subscribe my name this 10th day of July, 1930.
